Specification for Design.

Patented Aug. 14, 1917.

Application filed January 30, 1917. Serial No. 145,539. Term of patent 14 years.

To all whom it may concern:

Be it known that I, JOSEPH E. ROSENFELD, a citizen of the United States, and a resident of the city of Council Bluffs, county of Pottawattamie, and State of Iowa, have invented a new, original, and ornamental Design for Block-Holding Frames, reference being had to the accompanying drawing, forming part hereof, in which—

Figure 1 is a plan view of a block holding frame, showing my new design.

Fig. 2 is a side elevation of the same, and, Fig. 3 is a sectional view on the line 3—3 of Fig. 1, looking in the direction of the arrows.

I claim:—

The ornamental design for a block holding frame, as shown.

JOSEPH E. ROSENFELD.
